UNITED STATES PATENT OFFICE.

FORREST J. COUCH, OF ROCHESTER, NEW YORK, ASSIGNOR TO AMERICAN LAUNDRY MACHINERY COMPANY, OF ROCHESTER, NEW YORK, A CORPORATION OF NEW YORK.

IRONING-MACHINE.

1,238,891.

Specification of Letters Patent. Patented Sept. 4, 1917.

Application filed April 21, 1913. Serial No. 762,492.

To all whom it may concern:

Be it known that I, FORREST J. COUCH, of Rochester, in the county of Monroe and State of New York, have invented certain 5 new and useful Improvements in Ironing Machines.

My invention relates to ironing machines, and more particularly to the type employed for ironing shirts which include generally 10 a stationary heated chest or platen, and a movable presser adapted to be raised into engagement with the platen, the presser being provided with a bosom board and co-operating neck-band clamping devices, and 15 it has for its object to provide a novel construction, which enables the garment to be pressed with less liability of tearing between the neck-band and the bosom and yoke, than in machines as heretofore constructed. 20 A further object of my invention consists in the provision of an arrangement of parts such that a sufficient amount of heat is applied to the neck-band and to the portions 25 of the bosom and yoke immediately adjacent to the neck-band, so that the garment is more perfectly pressed at such portions, where there is often an accumulation of more or less dampness by reason of the ordinarily adopted arrangement of the neck-band 30 clamping devices with relation to the bosom board. Still a further object of my invention resides in arranging the neck-band clamping devices, as well as the yoke clamp, so that they may have a yielding movement 35 in a vertical direction with relation to the bosom board, when engaged by the stationary platen, upon raising the presser. To these and other ends the invention consists in certain improvements and combinations 40 of parts all as will be hereinafter more fully described, the novel features being pointed out in the claims at the end of the specification.

In the drawings: Figure 1 is a view in side 45 elevation illustrating a preferred embodiment of the invention, and showing the presser in its lower position, the neck-band clamping devices and the yoke clamp being engaged with the bosom board.

Fig. 2 is a similar view, the neck-band clamping devices and the yoke clamp being disengaged.

Fig. 3 is a plan view, showing a portion 50 of the bosom board.

Fig. 4 is a vertical, sectional view through

the stationary platen, the bosom board and yoke clamp.

Fig. 5 is a plan view of the bosom board, with the neck-band clamping devices removed.

Fig. 6 is an end elevation of the parts shown in Fig. 1.

Fig. 7 is a horizontal sectional view on the line 7^a—7^a of Fig. 6.

Fig. 8 is a transverse vertical sectional view through the stationary platen, the bosom board and neck-band clamping devices, showing the parts in operative engagement with the platen.

Fig. 9 is a view in end elevation of the 70 same, with the yoke clamp in position.

Fig. 10 is a detail plan view of the neck-band clamping devices.

Similar reference characters throughout the several views indicate the same parts.

The invention is illustrated in connection with the usual type of bosom press and for convenience, I have omitted the unnecessary parts which do not constitute any part of the invention, and it will be understood that 80 the usual means may be employed for heating the stationary platen, or steam chest, and for elevating the presser into engagement with the platen. In the present embodiment, showing a preferred form, A 85 designates generally the support for the presser, which is adapted to be raised and lowered into and out of engagement with the platen or steam chest B, which is hollow as shown in Fig. 8, and to which a heating medium may be supplied.

Arranged on the support A of the presser is the bosom board 1, which is slidably adjustable on the support and carries the expanding members 2 of the neck-band 95 clamping devices, whereby the machine may be adjusted for neck-bands of different sized shirts. The bosom board may be held in any adjusted position by suitable clamping devices, and the expanding members of 100 the neckband clamp are likewise held, as shown in co-pending application Serial No. 731,264, filed November 14, 1912, the details of which form no part of my present invention. The bosom board carries a dished plate 3, the latter being mounted on the pins 4 which engage suitable openings in the bosom board, the plate 3 being held in its normal position by means of the springs 5. Said plate 3, includes an upwardly extend- 110

ing central portion 6, which carries a transverse rod 7, engaging openings in the aforementioned expanding members 2, which are slideable inwardly and outwardly upon the rod 7. 8 designates a block which is arranged to engage the neck-band, and is resiliently supported upon the presser, preferably by means of suitable pins 9 carried by the block and engaging openings in the extension 10, which is suitably attached to the support. 11 are springs surrounding the pins 9, and which serve to hold the block normally in its upper position. The expanding members 2 carry pins 12 which engage openings in the block 8, said openings being convergently arranged as shown in Fig. 3, and serving to guide the expanding members 2 in their movement toward and from the block, as the bosom board is adjusted longitudinally for different sized neck-bands. The bosom board is provided with the usual padding 13, and by reference to Figs. 4 and 8, it will be observed that when the presser is moved upwardly into engagement with the platen, the padding is compressed, and where the neck-band is tightly clamped, the compression of the padding causes a pulling away of the bosom and yoke from the neck-band, imparting constant strain, and frequently resulting in tearing of the shirt at these points. With the present structure, however, when the padding on the bosom board is pressed down, the neck-band clamping devices may be correspondingly depressed, the block 8 and the expanding members 2 all being resiliently mounted so that they may move sufficiently to maintain a constant relation between the neck-band and the yoke and bosom of the shirt. In order to effect such movement of the neck-band engaging devices, the platen may be provided with a suitable extension to engage the top of the parts referred to, and I preferably accomplish this by extending the platen over said parts, and recessing it as indicated at 14, to afford an opening within which the neck-band, and the neck-band clamping devices may be received. The recessed portion of the platen being heated, imparts a sufficient amount of heat to the neck-band clamping devices to thoroughly dry and press the neck-band and the parts of the yoke and bosom immediately adjacent thereto, and the advantages thus derived constitute an important feature of my invention, as distinguished from prior constructions.

The neck-band clamping ring is indicated at 15, being mounted on a yoke 16, which is pivoted at 16^a, and carries a pinion 17. The latter is operated by a segmental rack 18 on the lever 19; which is pivoted at 20, and is operated through a connecting rod 21 in turn pivoted to the lever 22. Lever 22 is pivoted at 23 and carries a locking pawl 24

which co-operates with suitable projections 25 on the support, in order to hold the clamping ring in engagement with the neck-band until it is desired to release it.

26 is the yoke clamp provided with suitable padding 27 and pivotally supported on the rod 28, which is yieldably mounted by means of the spring 29 in the yoke 30. Said yoke 30 is pivotally supported at 31 upon a bracket 32 and is connected by means of toggle links 33 and 34 to the levers 35, which are pivoted at 36 upon the bracket. The toggle links 33 and 34 afford a toggle joint, which when closed, moves the yoke clamp into engagement with the bosom board, the different positions of the bosom board being provided for by means of the springs 37, which co-operate with the lower ends of the levers 35, as shown in Figs. 1 and 2. Closing of the toggle joint for operating the yoke clamp is effected by means of the lever 38, formed integral with one of the links 34, as shown in Fig. 3.

In the usual operation of the machine, the neck-band clamping ring is first positioned about the neck-band, and the yoke clamp is next brought into engagement. It is desirable to provide means whereby the yoke clamp may be released simultaneously with the return movement of the neck-band clamping ring, and to this end I provide a mechanism for breaking the toggle joint which holds the yoke clamp in position. Preferably, this consists of a slotted lever 39 having engagement with the pivot 40 and connected to a rod 41. The latter is pivotally arranged on the support at 42 and is adapted to be engaged by a tail piece 43 carried by the before mentioned lever 22. Thus when the lever 22 is moved to the position shown in Fig. 2, to release the neck-band clamping ring, the slotted lever 39 is forced upwardly far enough to break the toggle joint, and the yoke clamp is withdrawn from the bosom board by the action of the springs 44 which connect the yoke 30 and the levers 35. The lever 19, which effects operation of the neck-band clamping ring is returned to its normal position by means of the spring 45, engaging the end of the lever.

It will be seen that by this arrangement, the yoke clamp is also permitted a vertically yielding movement relatively to the bosom board, when it comes in contact with the recessed part of the heated platen, and when the presser is lowered the release of the lever 22 causes the yoke clamp and the neck-band clamping ring to be simultaneously restored to their normal positions.

While I have shown a particular embodiment of my invention, I do not limit myself to the precise construction disclosed, as other modifications and changes may be had without departing from the essential features of my improvements.

I claim as my invention:

1. In an ironing machine, the combination with a platen, of a movable presser adapted to be brought into engagement with the platen embodying a bosom board and neck band clamping devices vertically movable and resiliently supported on the presser, the platen being extended over the neck-band clamping devices having a recessed portion to receive and engage the upper surface of the neck-band clamping devices.
2. In an ironing machine, the combination with a platen, of a movable presser adapted to be brought into engagement with the platen embodying a bosom board and neck-band clamping devices vertically movable and resiliently supported on the presser, the platen having a portion arranged to engage the top of the neck-band clamping devices.
3. In an ironing machine, the combination with a relatively movable platen and presser adapted to be brought into engagement with one another, the presser embodying a bosom board, neck-band clamping devices including a resiliently supported expandible member movable bodily in a vertical direction, and a clamping ring having engagement with the expandible member.
4. In an ironing machine, the combination with a platen, of a movable presser adapted to be brought into engagement with the platen embodying a support, a bosom board movable lengthwise of the support, a pair of expanding members resiliently supported on the bosom board, and movable therewith, a neck-band engaging block resiliently mounted on the support, and a neck-band clamping ring arranged to engage said block.
5. In an ironing machine, the combination with a platen, of a movable presser adapted to be brought into engagement with the platen embodying a bosom board, neck-band clamping devices including an expandible member, and a yoke clamp arranged to engage the bosom board, the yoke clamp and expandible member being yieldable in a vertical plane relatively to the bosom board.
6. In an ironing machine, the combination with a platen, of a movable presser adapted to be brought into engagement with the platen embodying a support, a bosom board movable on the support, neck-band clamping devices including a block resiliently mounted on the support, and expanding members resiliently mounted on the bosom board and guided upon said block.
7. In an ironing machine, the combination with a platen, of a movable presser adapted to be brought into engagement with the platen embodying a support, a bosom board movable on the support, neck-band clamping devices including a block resiliently mounted on the support, expanding members resiliently mounted on the bosom board and guided upon said block and a yoke clamp arranged to engage the bosom board and having a vertically yieldable movement relatively to the same.
8. In an ironing machine, the combination with a platen, of a movable presser adapted to be brought into engagement with the platen embodying a support, a bosom board movable on the support, neck-band clamping devices including a resiliently mounted expandible member, and a yoke clamp arranged to engage the bosom board and yieldable vertically in relation to the same.
9. In combination with a bosom board and a neck-band engaging block, of a neck-band clamping ring, means for operating the neck-band clamping ring, a yoke clamp, actuating devices for the yoke clamp including a toggle joint, and a mechanism controlled by the release of the neck-band clamping ring for breaking said toggle joint to release the yoke clamp.
10. In an ironing machine, the combination with a relatively movable platen and presser adapted to be brought into engagement with one another, the presser embodying a bosom board and neck-band clamping devices disposed thereabove, the platen being recessed and extended over the neck-band clamping devices and having engagement with the top of the latter.
11. In an ironing machine, the combination with a relatively movable platen and presser adapted to be brought into engagement with one another, the presser embodying a bosom board and neck-band clamping devices supported thereon and movable bodily in a vertical direction, the platen extending over the neck-band clamping devices and having a recessed portion to receive and engage the upper surface thereof.
12. In an ironing machine, the combination with a relatively movable platen and presser adapted to be brought into engagement with one another, the presser embodying a pair of expanding members resiliently supported and having movement bodily in a vertical direction, a neck-band engaging block resiliently mounted and having movement bodily in a vertical direction, and a neck-band clamping ring having engagement with the block, the platen having a recessed portion to receive and engage the upper surface of the expanding members and block.
13. In an ironing machine, the combination with a relatively movable platen and presser adapted to be brought into engagement with one another, the presser embodying a bosom board, a pair of expanding members mounted thereon and having movement bodily in a vertical direction with relation to the board, a neck-band engaging block having movement bodily in a vertical direction with relation to the board, and

a neck-band clamping ring having engagement with the block, the platen having a recessed portion to receive and engage the upper surface of the expanding members and block.

14. In an ironing machine, the combination with a relatively movable platen and presser adapted to be brought into engagement with one another, the presser embodying a bosom board and a yoke clamp arranged to engage the bosom board, the yoke clamp being movable in a vertical plane relatively to the bosom board.

15. In an ironing machine, the combination with a relatively movable platen and 15 presser adapted to be brought into engagement with one another, the presser embodying a bosom board, and a yoke clamp resiliently supported to engage the bosom board and yieldable in a vertical plane with relation thereto? 20
